TRANSMITTER

Albert F. Horlacher, Genoa, Ill., assignor to Automatic Electric Laboratories, Inc., a corporation of Delaware

Application July 9, 1941, Serial No. 401,592

11 Claims. (Cl. 179—122)

The present invention relates to transmitters and more particularly to telephone transmitters.

A conventional telephone transmitter is responsive to sound waves of different frequencies disposed within the audible range and including background sound waves having frequencies disposed within a first band in the audible range and signal sound waves having frequencies disposed in a second band in the audible range. Ordinarily, the background sounds or noises have frequencies disposed toward the lower end of the audible range; while the signal sounds have frequencies disposed toward the higher end of the audible range. Consequently, the telephone transmitter transmits sound energy corresponding both to the background noises and to the signal sounds, thereby to cause a telephone receiver associated with the telephone transmitter to reproduce both the background noises and the signal sounds.

Accordingly, it is an object of the present invention to provide a transmitter embodying an improved arrangement for preventing the transmitter from transmitting sound energy corresponding to the background noises.

Another object of the invention is to provide in a transmitter, an improved mechanical filter arrangement for filtering out undesirable noises having frequencies disposed within a predetermined band in the audible range of the transmitter.

Another object of the invention is to provide a transmitter embodying an improved acoustic arrangement which is effective to increase the sound energy transmitted thereby within a predetermined band toward the low frequency end of the operating range thereof.

A further object of the invention is to provide in a transmitter, an improved acoustic-mechanical arrangement which is effective to produce a high degree of uniformity of response over the entire operating frequency range thereof.

A further object of the invention is to provide a transmitter which is of simple and rugged structure and which is of compact and light-weight construction.

The novel features believed to be characteristic of the invention are set forth with particularity in the appended claims. The invention, both as to its organization and method of operation, together with further objects and advantages thereof, will best be understood by reference to the following specification taken in connection with the accompanying drawing, in which Figure 1 is a plan view of a telephone

transmitter embodying the present invention; and Fig. 2 is a longitudinal sectional view of the transmitter taken along the line 2—2 in Fig. 1.

Referring now more particularly to Figs. 1 and 2 of the drawing, there is shown a telephone transmitter 10 which comprises a hollow casing, including a cup-shaped member 11 provided with a cylindrical side wall 12 and an annular top wall 13, the exterior surface of the side wall 12 being threaded as indicated at 14 for reception in a suitable support, not shown. The casing also comprises a tubular member 15 constituting a bottom wall, the member 15 being provided with an outwardly extending annular flange 16. Preferably, the cup-shaped member 11 and the tubular member 12 are formed of a suitable aluminum alloy and are retained in assembled relation by an arrangement comprising two insulating rings 17 and 18 and a metallic ring 19. More particularly, the insulating ring 17 is arranged within an annular recess 12a provided in the interior of the side wall 12 adjacent the end thereof, the insulating ring 17 having an annular recess 11a therein receiving the annular flange 16. The insulating ring 18 is interposed between the annular flange 16 and the metallic ring 19, whereby the tubular member 15 and the annular flange 16 carried thereby are electrically insulated from the side wall 12 of the cup-shaped member 11. Finally, the tubular member 15 is retained in place in a clamped condition between the insulating rings 17 and 18 due to pressure exerted by the metallic ring 19, the metallic ring 19 being retained in place by a spun-over bead 12b provided on the outer end of the side wall 12.

Also, the transmitter 10 comprises upper and lower movable electrodes 20 and 21, respectively. The upper electrode 20 has a cup-shaped configuration and is resiliently mounted within the casing of the transmitter 10 by an arrangement comprising a first resilient member 22 extending between the peripheral portion of the electrode 20 and an inwardly disposed and downwardly projecting flange 23 carried by the top wall 13 of the member 11. Preferably, the resilient member 22 has a bellows-like construction and is formed of paper, the lower end of the resilient member 22 being sealed to the adjacent peripheral portion of the electrode 20 and the upper end of the resilient member 22 being sealed to the lower face of the annular flange 23. The upper electrode 20 is arranged in spaced relation with respect to the top wall 13, whereby a first chamber 24 is defined within the casing of the transmitter 10 by the upper electrode 20, the re-

silent member 22, the annular flange 23 and the top wall 13.

Similarly, the lower electrode 21 has a cup-shaped configuration and is resiliently mounted within the casing of the transmitter 10 by an arrangement comprising a second resilient member 25 extending between the peripheral portion of the electrode 21 and an inwardly disposed and upwardly projecting flange 26 carried by the member 15. Preferably, the resilient member 25 has a bellows-like construction and is formed of paper, the upper end of the resilient member 25 being sealed to the adjacent peripheral portion of the electrode 21 and the lower end of the resilient member 25 being sealed to the upper face of the annular flange 26. The tubular member 15 has an annular opening 15a formed therein, which is sealed by an annular plug 27, the plug 27 being sealed in place by a spun-over bead 15b provided on the outer end of the member 15. The lower electrode 21 is arranged in spaced relation with respect to the plug 27, whereby a second chamber 28 is defined within the casing of the transmitter 10 by the lower electrode 21, the resilient member 25, the annular flange 26, the member 15 and the plug 27.

The upper and lower electrodes 20 and 21 are arranged in spaced relation and are connected together by a third resilient member 29 extending therebetween. Preferably, the resilient member 29 has a bellows-like construction and is formed of paper, the upper end of the resilient member 29 being sealed to the adjacent peripheral portion of the upper electrode 20 and the lower end of the resilient member 29 being sealed to the adjacent peripheral portion of the lower electrode 21. The upper and lower electrodes 20 and 21 and the resilient member 29 cooperate to define a compartment 30 therebetween, which contains a quantity of granulated carbon 31 constituting a variable impedance element. The central portion of the upper electrode 20 has an opening formed therein which is sealed by a suitable metallic plug 32. Similarly, the central portion of the lower electrode 21 has an opening formed therein which is sealed by a suitable metallic plug 33. Further it is noted that a metallic weight 34 is arranged within the second chamber 28 and secured to the lower electrode 21 by an arrangement comprising a screw 35. More particularly, the head of the screw 35 is arranged within a recess 34a provided in the weight 34, while the shank of the screw 35 is arranged in threaded engagement with respect to a tapped hole provided in the plug 33.

Preferably, the upper and lower electrodes 20 and 21 are formed of a suitable electrical conducting material, such as carbon, and are respectively electrically connected to the members 11 and 15, which members form the two electrical terminals of the transmitter 10. More particularly, the upper electrode 20 is electrically connected to the top wall 13 of the member 11 by a flexible conductor 36; and the lower electrode 21 is electrically connected to the member 15 by a flexible conductor 37 extending between the member 15 and the weight 34.

The side wall 12, the top wall 13, the insulating ring 17, the annular flange 16, the annular flanges 23 and 26, the electrodes 20 and 21 and the resilient members 22, 25 and 29 cooperate to define a third chamber 38 within the casing of the transmitter 10 disposed in surrounding relationship with respect to the electrodes 20 and 21 and the chambers 24 and 28. Four annularly dis-

posed openings 39 are formed in the top wall 13 and communicate between the exterior and the first chamber 24; while four annularly disposed openings 40 are formed in the top wall 13 and communicate between the exterior and the third chamber 38. Finally, a series of spaced-apart openings 41 are formed in the annular flange 26 and communicate between the second chamber 28 and the third chamber 38. Accordingly, the openings 39 provide a direct restricted passage between the exterior and the first chamber 24, whereby the movement of the upper electrode 20 may be controlled by sound-pressure waves; while the openings 40 and 41 provide a series restricted passage through the third chamber 38 between the exterior and the second chamber 28, whereby the movement of the lower electrode 21 may be controlled by sound-pressure waves.

During the operation of the transmitter 10 the sound-pressure waves entering the first chamber 24 act upon the upper electrode 20 in order to cause vibration thereof; and the sound-pressure waves entering the second chamber 28 act upon the lower electrode 21 in order to cause vibration thereof, whereby the quantity of granulated carbon 31 disposed in the compartment 30 formed between the electrodes 20 and 21 is compressed to a degree determined by the relative movement of the electrodes 20 and 21 in order to vary the terminal impedance of the transmitter in accordance with the sound waves acting thereon. Preferably, the mass-stiffness of the lower electrode and its resilient mounting, as determined primarily by the stiffness of the resilient member 25, the mass of the electrode 21, the plug 33, the weight 34 and the screw 35, is of such a value that the lower electrode 21 is moved with the upper electrode 20 by forces acting through the quantity of granulated carbon 31 within a predetermined band toward the low frequency end of the operating range of the transmitter 10, whereby the relative movement between the upper and lower electrodes 20 and 21 is minimized in the predetermined band mentioned in order to filter out background noises disposed within this frequency band. Also, the dimensions of the series passage communicating between the exterior and the second chamber 28, including the openings 40 and 41 and the third chamber 38, are so proportioned and related that it offers a relatively high impedance to the passage of sound-pressure waves within a given band toward the high frequency end of the operating range of the transmitter 10, whereby sound-pressure waves within the given band mentioned have a minimum action upon the lower electrode 21, this series passage being effectively blocked at frequencies within this frequency band.

In a preferred embodiment of the transmitter 10, the mass-stiffness of the lower electrode 21 and its resilient mounting is of such a value that the lower electrode 21 has a fundamental resonance frequency of the order of 800 cycles per second; and the mass-stiffness of the upper electrode 20 and its resilient mounting is of such a value that the upper electrode 20 has a fundamental resonance frequency of the order of 1500 cycles per second. The value of the mass-stiffness of the lower electrode 21 and its resilient mounting is determined primarily by the stiffness of the resilient member 25 and the mass of the electrode 21, the plug 33, the weight 34 and the screw 35, as previously noted; and may be altered by appropriately varying the mass of the weight 34 in an obvious manner. In a like man-

ner, the value of the mass-stiffness of the upper electrode 21 and its resilient mounting is determined primarily by the stiffness of the resilient member 22 and the mass of the upper electrode 20 and the plug 32. Also, the stiffness reactance of the first chamber 24 is so proportioned and related with respect to the mass reactance of the direct communicating passage, including the openings 39, that the column of air in the first chamber 24 has an effective resonance frequency of the order of 2500 cycles per second; while the stiffness reactance of the second chamber 28 is so proportioned and related with respect to the mass reactance of the series communicating passage, including the openings 40 and 41 and the third chamber 38, that the column of air in the second chamber 28 has an effective resonance frequency of the order of 3000 cycles per second. Accordingly, in the preferred embodiment of the transmitter 10, the output response characteristic thereof has four peaks occurring approximately at 800, 1500, 2500 and 3000 cycles per second due to the factors mentioned above.

Moreover, in the preferred embodiment of the transmitter 10, the mass-stiffness of the lower electrode 21 and its resilient mounting is of such a value that the lower electrode 21 is moved with the upper electrode 20 by forces acting through the quantity of granulated carbon 31 at frequencies disposed below a frequency of the order of 500 cycles per second, thereby to establish an effective cutoff point at this frequency such that low frequency background noises below the cutoff point are not transmitted by the transmitter 10. Finally, in the preferred embodiment of the transmitter 10, the mass reactance of the series passage, including the openings 40 and 41 and the third chamber 38, is of such a value that frequencies above a frequency of the order of 4000 cycles per second are trapped in the third chamber 38 and not transmitted to the second chamber 28, whereby the lower electrode 21 is not materially acted upon by frequencies above a frequency of the order of 4000 cycles per second in the operating range of the transmitter 10.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. A transmitter comprising a hollow casing, first and second movable electrodes disposed within said casing, means including a first resilient member for supporting said first electrode within said casing and cooperating with said first electrode and the walls of said casing to define a first chamber within said casing, means including a second resilient member for supporting said second electrode within said casing and cooperating with said second electrode and the walls of said casing to define a second chamber within said casing, a third resilient member extending between said electrodes and cooperating therewith to define a compartment therebetween, a variable impedance element arranged within said compartment, the effective impedance of said element being governed in accordance with the relative movement between said electrodes, the walls of said casing cooperating with both of said electrodes and all three of said resilient elements to define a third chamber therein, a first opening formed in said casing and provid-

ing a direct restricted passage between the exterior and said first chamber, whereby the movement of said first electrode may be controlled by sound-pressure waves, and second and third openings formed in said casing and providing a series restricted passage through said third chamber between the exterior and said second chamber, whereby the movement of said second electrode may be controlled by sound-pressure waves.

2. A transmitter comprising a cylindrical hollow casing including a side wall and top and bottom walls, said top wall carrying an inwardly disposed and downwardly projecting annular flange, said bottom wall carrying an inwardly disposed and upwardly projecting annular flange, upper and lower movable electrodes disposed within said casing, means including a first resilient member extending between said downwardly projecting flange and said upper electrode for supporting said upper electrode within said casing and cooperating therewith to define a first chamber within said casing, means including a second resilient member extending between said upwardly projecting flange and said lower electrode for supporting said lower electrode within said casing and cooperating therewith to define a second chamber within said casing, a third resilient member extending between said electrodes and cooperating therewith to define a compartment therebetween, a variable impedance element arranged within said compartment, the effective impedance of said element being governed in accordance with the relative movement between said electrodes, the side wall and the top and bottom walls of said casing cooperating with both of said flanges and both of said electrodes and all three of said resilient elements to define a third chamber therein, a first restricted passage formed in said casing and communicating directly between the exterior and said first chamber, whereby the movement of said first electrode may be controlled by sound-pressure waves, and a second restricted passage formed in said casing and communicating through said third chamber between the exterior and said second chamber, whereby the movement of said second electrode may be controlled by sound-pressure waves.

3. A transmitter comprising a hollow casing, a first movable electrode resiliently mounted within said casing, a second movable electrode resiliently mounted within said casing, a first chamber defined in said casing adjacent said first electrode, a second chamber defined in said casing adjacent said second electrode, a first restricted passage formed in said casing and communicating between the exterior and said first chamber, whereby the movement of said first electrode may be controlled by sound-pressure waves, a second restricted passage formed in said casing and communicating between the exterior and said second chamber, whereby the movement of said second electrode may be controlled by sound-pressure waves, the dimensions of said second passage being so proportioned and related that it offers a relatively high impedance to the passage of sound-pressure waves within a given frequency band in the operating range of the transmitter, and a variable impedance element arranged between said electrodes, the effective impedance of said element being governed in accordance with the relative movement between said electrodes.

4. A transmitter comprising a hollow casing,

a first movable electrode resiliently mounted within said casing, a second movable electrode resiliently mounted within said casing, a first chamber defined in said casing adjacent said first electrode, a second chamber defined in said casing adjacent said second electrode, a first restricted passage formed in said casing and communicating between the exterior and said first chamber, whereby the movement of said first electrode may be controlled by sound-pressure waves, a second restricted passage formed in said casing and communicating between the exterior and said second chamber, whereby the movement of said second electrode may be controlled by sound-pressure waves, the dimensions of said second passage being so proportioned and related that it offers a relatively high impedance to the passage of sound-pressure waves within a given band toward the high frequency end of the operating range of the transmitter, and a variable impedance element arranged between said electrodes, the effective impedance of said element being governed in accordance with the relative movement between said electrodes.

5. A transmitter comprising a hollow casing, a first movable electrode resiliently mounted within said casing, a second movable electrode resiliently mounted within said casing, a first chamber defined in said casing adjacent said first electrode, a second chamber defined in said casing adjacent said second electrode, a first restricted passage formed in said casing and communicating between the exterior and said first chamber, whereby the movement of said first electrode may be controlled by sound-pressure waves, a second restricted passage formed in said casing and communicating between the exterior and said second chamber, whereby the movement of said second electrode may be controlled by sound-pressure waves, and a variable impedance element arranged between said electrodes, the effective impedance of said element being governed in accordance with the relative movement between said electrodes, the mass-stiffness of said second electrode and its resilient mounting being of such a value that said second electrode is moved with said first electrode by forces acting through said element at frequencies within a predetermined band in the operating range of the transmitter.

6. A transmitter comprising a hollow casing, a first movable electrode resiliently mounted within said casing, a second movable electrode resiliently mounted within said casing, a first chamber defined in said casing adjacent said first electrode, a second chamber defined in said casing adjacent said second electrode, a first restricted passage formed in said casing and communicating between the exterior and said first chamber, whereby the movement of said first electrode may be controlled by sound-pressure waves, a second restricted passage formed in said casing and communicating between the exterior and said second chamber, whereby the movement of said second electrode may be controlled by sound-pressure waves, and a variable impedance element arranged between said electrodes, the effective impedance of said element being governed in accordance with the relative movement between said electrodes, the mass-stiffness of said second electrode and its resilient mounting being of such a value that said second electrode is moved with said first electrode by forces acting through said element at frequen-

cies within a predetermined band toward the low frequency end of the operating range of the transmitter.

7. A transmitter comprising a hollow casing, a first movable electrode resiliently mounted within said casing, a second movable electrode resiliently mounted within said casing, a first chamber defined in said casing adjacent said first electrode, a second chamber defined in said casing adjacent said second electrode, a first restricted passage formed in said casing and communicating between the exterior and said first chamber, whereby the movement of said first electrode may be controlled by sound-pressure waves, a second restricted passage formed in said casing and communicating between the exterior and said second chamber, whereby the movement of said second electrode may be controlled by sound-pressure waves, and a variable impedance element arranged between said electrodes, the effective impedance of said element being governed in accordance with the relative movement between said electrodes, the mass-stiffness of said second electrode and its resilient mounting being of such a value that said second electrode is moved with said first electrode by forces acting through said element at frequencies within a predetermined band in the operating range of the transmitter, the dimensions of said second passage being so proportioned and related that it offers a relatively high impedance to the passage of sound-pressure waves within a given frequency band in the operating range of the transmitter.

8. A transmitter comprising a hollow casing, a first movable electrode resiliently mounted within said casing, a second movable electrode resiliently mounted within said casing, a first chamber defined in said casing adjacent said first electrode, a second chamber defined in said casing adjacent said second electrode, a first restricted passage formed in said casing and communicating between the exterior and said first chamber, whereby the movement of said first electrode may be controlled by sound-pressure waves, a second restricted passage formed in said casing and communicating between the exterior and said second chamber, whereby the movement of said second electrode may be controlled by sound-pressure waves, and a variable impedance element arranged between said electrodes, the effective impedance of said element being governed in accordance with the relative movement between said electrodes, the mass-stiffness of said second electrode and its resilient mounting being of such a value that said second electrode is moved with said first electrode by forces acting through said element at frequencies within a predetermined band toward the low frequency end of the operating range of the transmitter, the dimensions of said second passage being so proportioned and related that it offers a relatively high impedance to the passage of sound-pressure waves within a given band toward the high frequency end of the operating range of the transmitter.

63 9. A transmitter comprising a hollow casing including an annular side wall and top and bottom walls, an upper electrode resiliently mounted with respect to said top wall, a lower electrode 70 resiliently mounted with respect to said bottom wall, and resilient means separating said electrodes, said casing and said upper electrode being formed with said first-mentioned resilient mounting to provide an upper chamber above 75 said upper electrode, said casing and said lower

electrode being formed with said second-named resilient mounting to provide a lower chamber below said lower electrode, said casing having parts cooperating with said electrodes and said resilient means and said resilient mountings to form an annular chamber surrounding said electrodes, said casing having a passage forming a communication between said upper chamber and the exterior of said casing, said casing having other passages forming restricted communications between the exterior of said casing and said annular chamber and between said annular chamber and said lower chamber.

10. A transmitter comprising a hollow casing including an annular side wall and top and bottom walls, said bottom wall being insulated from said other walls, an upper electrode resiliently mounted with respect to said top wall, a lower electrode resiliently mounted with respect to said bottom wall, resilient means separating said electrodes, said casing and said upper electrode being formed with said first-named resilient mounting to provide an upper chamber above said upper electrode, said casing and said lower electrode being formed with said second-named resilient mounting to provide a lower chamber below said lower electrode, said casing having parts cooperating with said electrodes and said resilient means and said resilient mountings to form an annular chamber surrounding said electrodes, said casing having a passage forming a communication between said upper chamber and the exterior of said casing, said casing having other passages

5 forming restricted communications independently of the upper chamber between the exterior of said casing and the annular chamber and between said annular chamber and said lower chamber, means for forming an electrical connection between said casing and said upper electrode, and means for forming an electrical connection between said bottom wall and said lower electrode.

11. A transmitter comprising a hollow casing 10 including an annular side wall and top and bottom walls, an upper electrode resiliently mounted with respect to said top wall, a lower electrode resiliently mounted with respect to said bottom wall, resilient means separating said electrodes, said casing and said upper electrode being formed with said first-mentioned resilient mounting to provide an upper chamber above said upper electrode, said casing and said lower electrode being formed with said second-named resilient mounting to provide a lower chamber below said lower electrode, said casing having parts cooperating with said electrodes and said resilient means and said resilient mountings to form an annular chamber surrounding said electrodes, said casing having a passage forming a communication between said upper chamber and the exterior of said casing, said casing having other passages forming restricted communications between the exterior of said casing and said annular chamber and between said annular chamber and said lower chamber, and a weight detachably secured to said lower electrode within said lower chamber.

ALBERT F. HORLACHER.
